UNITED STATES PATENT OFFICE.

GUSTAF ALFRED HENDRICKSON AND MARTIN HENDRICKSON, OF CHICAGO, ILLINOIS.

BOTTLING-MACHINE.

1,237,038.

Specification of Letters Patent. Patented Aug. 14, 1917.

Application filed March 8, 1916. Serial No. 82,852.

To all whom it may concern:

Be it known that we, GUSTAF ALFRED HENDRICKSON and MARTIN HENDRICKSON, citizens of the United States of America, and residents of Chicago, county of Cook, and State of Illinois, have invented certain new and useful Improvements in Bottling-Machines, of which the following is a specification.

10 This invention relates to bottling machines, particularly those adapted for filling and capping milk bottles in groups of two or more, and preferably a whole case at a time, the cases being fed automatically to the machine and removed in like manner. This application embodies matter divided out of our application which matured in Patent No. 1,179,372, dated April 11, 1916, wherein certain parts of the machine not 20 claimed herein are more fully set forth and described, and also embodies certain improvements on the machine disclosed in said patent.

The main objects of this invention are to 25 provide automatic capping means of improved form; to provide improved means for transferring the caps from the cap magazines to the several points of application to the bottles respectively; to provide 30 for raising the bottle cases momentarily to a capping position after filling; to provide improved centering means for registering the several bottles in alinement with the cappers respectively when the bottles are so 35 raised; to provide improved means for guiding and applying the caps to the mouths of the bottles; to provide improved means for feeding the bottle cases to the machine and for discharging the same; and to provide 40 improved means for starting and stopping the machine.

An illustrative embodiment of this invention is shown in the accompanying drawings, in which—

45 Figure 1 is a fragmentary vertical section of the machine approximately on the line A—A of Fig. 2.

Fig. 2 is a fragmentary top view of the machine.

50 Fig. 3 is an enlarged fragmentary cross-section of the machine on the line B—B of Fig. 2, showing the principal features of the capper feed mechanism.

55 Fig. 4 is an enlarged fragmentary axial section on the line C—C of Fig. 2, showing one of the filler tubes and the corresponding

capper in its raised position, the latter being indicated also by dotted lines in its lowered position.

Fig. 5 is a plan of the stationary frame 60 plate or table at the foot of the cap magazines, whereon the latter are mounted.

Fig. 6 is a plan of the oscillatory frame or swinging table which carries the combined cap guides and centering bells. 65

Fig. 7 is a side view of the cam which raises and lowers the bottle lifting and supporting platform.

Fig. 8 is a plan of one of the four cap feeders. 70

Fig. 9 is an axial section on the line D—D of Fig. 2 at the base of one of the cap magazines, the cap feeder being in its retracted position with its cap apertures in registry with the corresponding magazines. 75

Fig. 10 is a section on the line E—E of Fig. 2 showing a detail of the bulkhead.

Fig. 11 is an axial section of the combined filling and cap setting means.

Fig. 12 is a fragmentary sectional plan of 80 the machine on the line F—F of Fig. 13.

Fig. 13 is a fragmentary vertical section approximately on the line G—G of Fig. 12.

Fig. 14 is an enlarged perspective view of the yielding stop which controls the admission of cases to the machine. 85

Fig. 15 is a circuit diagram of the electrical connections for starting and stopping the machine automatically.

Fig. 16 is a fragmentary axial section of 90 the valve and filler tube, wherein the liquid ports are at the extreme lower end of said tube.

In the construction shown, the machine comprises a stationary frame 1, on which 95 there is mounted a milk supply tank 2, a bulkhead 3 connected with said tank, a platform 4 for the bottles 5, bottle filling means 6 communicating with said bulkhead, cap magazines 7, capping means including oscillatory guides 8 and cap setting plungers 9, means 15 for feeding caps 16 one at a time from each magazine to its respective guide 8, case feeding means 17, and correlated mechanisms for operating the several said 100 members automatically in accordance with a predetermined sequence and time ratio.

The frame 1 may be of any suitable construction adapted for supporting the several parts and mechanisms above mentioned, and 110 hereinafter more fully described. Said frame comprises mainly a plurality of up-

rights 18 and cross-members 20 rigidly jointed together. The part of the frame which supports the filler and capper mechanism proper may to advantage be detachable from the rest of the frame. Hence this part of the frame is carried on the plate 1' which is secured demountably to the rest of the frame.

The tank or reservoir 2 is mounted at the 10 top of an upwardly projecting part of the frame at one side of and above the rest of the machine, and comprises sides 21 and a bottom 22 having an outlet 23 communicating with the discharge tube 24 which leads 15 to the distributing chamber or bulkhead 3, which is disposed at one side of said tank and above the filling and capping mechanism.

The distributing bulkhead 3 for the fillers 20 is relatively shallow and is disposed horizontally over the bottling apparatus. It comprises a bottom 25, sides 26, and a detachable cover 27, secured normally in place, the joint for said cover having a gasket 28. Said bulkhead has outlets in its base for the 25 discharge of liquid as will be more fully described. Apertures are provided extending entirely through said bulkhead, which apertures have walls 30, the upper edges of 30 which are provided with gaskets 31, to fit against the cover 27, said apertures being provided to accommodate the cap magazines 7 hereinafter described. Said cover 27 is provided also with a plurality of small perforations in which are fixed small tubes 33 corresponding in number and location with the filling means 6. Said tubes 33 communicate with the bulkhead and project upward to a height substantially level with 40 the top of the supply reservoir 2, the purpose of said tubes being hereinafter more fully explained. The bulkhead is supported on the frame bars 34.

The bottle platform or case lifter 4 is 45 carried on supporting means 35, by which it may be raised and lowered automatically as required. The empty bottles 5 are first placed in open cases 36 having perforated or mesh bottoms 37, each case containing the 50 number of bottles for which the particular machine is adapted, which in this instance is twelve. Means are provided for sliding said cases into and out of the machine over said platform, either on rollers carried by 55 the brackets 39 as set forth in our said co-pending application, or by the automatic feed means 17, shown in Fig. 13. When the platform 4 is raised, it bears on the case bottom and supports the bottles firmly during 60 the filling and capping process, the platform bearing upward directly on the bottom 37 without lifting the sides of the case.

The filling means 6 comprises a plurality of tubes projecting downwardly from said bulkhead, one for each bottle, the number in

this instance being twelve. Each of said tubes is telescopic in character, the upper part or section 40 being attached tightly to the bottom at a corresponding perforation in the under side of the bulkhead with which it communicates, and the lower part 42 being reciprocatable downwardly and upwardly to and from its bottle filling position respectively.

Combined centering and closure means for the bottles are associated telescopically with the filler tubes, each comprising an annular member or sleeve 44 surrounding the lower end of the filler tube, and having a bell shaped centering and cushion member 45, 80 preferably in the form of a rubber gasket adapted to fit tightly over the mouth of the bottle so as to center the latter initially and prevent leakage of milk during the filling operation. Valve means hereinafter described are used for lifting said member 44 with the tube 42 when the filling operation is completed, and also yieldable means 47 for forcing said closure member down into tight contact with the bottle when the tube 42 is lowered. The cylindrical capping plunger 9, hereinafter described, is disposed slidably between a valve cylinder 49 and closure member 44 in liquid tight relation.

The said lifting means for said closure member 44 comprises the valve cylinder 49 fitting slidably over said tube 42 and within said plunger 9, which cylinder is seated normally at its lower end on an upwardly facing annular shoulder or seat 50 on the tip 100 of said tube, and rods 51 connecting said member 44 with the upper end of said cylinder 49, which is enlarged at 52 and provided with lugs 53 for attaching said rods. The coiled spring 47 surrounds the upper 105 part of tube 42 and seats at its lower end against the shoulder 54 of cylinder 49 and at its upper end against a flange 42' on tube 42 so as to urge the closure member 44 downward and also permit the tube 42 to continue 110 downward when member 44 has reached its seat on the bottle mouth and the valve cylinder 49 is thereby arrested. Such further lowering of the tube 42 opens the discharge ports 56, and permits the liquid to flow into 115 the bottle.

Valve mechanism for each filling tube is provided as follows: The lower end of each tube 42 is closed at the bottom 55, but has lateral apertures 56 closed normally by the lower part of said valve cylinder 49. When the tube 42 enters the bottle the withholding of cylinder 49 by the cap closure member 44 serves to open the valve ports 56, which, however, are closed automatically by the 120 subsequent rising of tube 42 within the cylinder 49 which seats normally on the shoulder 50.

In order that the air in the bottle may 125 pass out freely when the liquid enters, there 130

is provided in the filling tube 42 a long narrow air tube 58, having its lower end fitted tightly to the tube bottom 55 in registry with a perforation therein, and having its upper 5 end disposed in one of the tubes 33 projecting at all times above the surface of the liquid in the tank 2. A float valve 59 is held in the lower part of tube 58 which is enlarged and has a downwardly facing valve 10 seat 58'. This valve prevents liquid from rising in the air vent 58 when the bottle is full.

Each of the cap magazines 7 comprises a cylindrical base member 60 mounted rigidly 15 by means of the plate 61 and an interchangeable cylindrical member 62 fitting upon and readily removable from the base 60, the lower end of cylinder 62 fitting telescopically within the upward flange 63 of member 20 60. The interchangeable members 62 project upwardly through the apertures in bulk-head 3, and may be interchanged manually by lifting and lowering the same through the sleeves 30. The caps 16 fit loosely in each 25 magazine and feed downward by gravity, subject to removal successively by certain automatic feed mechanism hereinafter described.

Each of the guide means 8 comprises a 30 vertically disposed cylindrical member 65 associated with which at its lower end in vertically slidable relation is an outwardly flanged and downwardly facing bell-shaped member 66 adapted to fit over and center the 35 top of the bottle to be capped when such bottle is thrust upward thereunder. In order to compensate for limited variation in the height of the bottles, said guide member is provided with yielding means 67 arranged 40 to urge the centering "bell" 66 downwardly, but permitting the same to rise somewhat according to the height of the bottle, a coiled spring disposed about said guide member being preferred.

45 The guide 65 has a supporting flange 65' at its upper end, and the bell 66 has a top flange 66' screwed thereto by which it is supported, said guide and bell members being normally nested together with one flange 50 resting on the other. When the members 65 and 66 are swung over the bottle and the latter raised, they both fit against the bottle top and are each lifted more or less according to the shape and height of the bottle, 55 and may rise through the frame plate perforation 68 through which the feeder tube 42 and capper 9 project when each is operated. Each cap guide 65 is somewhat smaller than the caps 16, so that the latter 60 are prevented from dropping through prematurely. The upper end of cylinder 65 is enlarged or beveled at 65' so as to receive and hold a cap loosely until pushed down by the cap setting plunger 9. The guide 65 65 is beveled at its lower edge to fit the mouth

of the bottle, and is long enough to insure contact with the bottle before bell 66 makes contact, so that the cap is guided all the way to its seat in the mouth of the bottle.

Means are provided for supporting and 70 swinging said guide members each from its normal position adjacent to but eccentric with respect to its cap-magazine respectively to its discharge position over the bottle to be capped and in registry with the said perforation 68 in plate 61 and back again. Said carrying means in this instance comprises a swinging table or frame 69 of rectangular shape formed with twelve apertures 69' in which the said guide members are 80 mounted. The frame 69 is oscillatably mounted on a set of four arms 72 swinging on fixed pivots 73 set on the frame plate 1'. Two of said members 72 are provided with actuating arms 74 disposed at an angle with 85 respect to the frame supporting arms and forming therewith substantially a pair of bell crank levers. The free ends of said actuating arms are connected to a rod 75 which is actuated and controlled, as hereinafter described, to rock said arms through a suitable angle depending upon the precise relative position of the pivots 73, cap feeders 15 and plungers 9. (See Figs. 2 and 6.) Said table 69 is open or apertured at 69'', laterally of 90 the apertures 69' and in registry with the bottles and filling means when swung to its 95 cap receiving position.

The cap feeding means 15 for each group of magazines is reciprocating in its action, 100 and in this instance comprises a thin plate of somewhat smaller thickness than the caps, said plate being disposed cross-wise of the frame 1 and extending beneath a row of three magazines. Each plate 15 has perforations 77 spaced apart according to the spacing of said magazines, each of the apertures being substantially equal to or somewhat larger than the inner diameter of the magazine 7, so as to readily receive the caps successively. Means are provided for sliding each plate 15 forward sufficiently to bring each of its apertures into registry with the corresponding guides 8 in their retracted or 105 normal position. The caps carried in said apertures drop through the perforations 78 in the frame plate 61, and into the upper ends 65' of the guide cylinders 65. The said plates 15 are then restored automatically to their normal position and each perforation receives another cap ready to repeat the operation. The actuating means for the feed plates 15 drives them all simultaneously, which means is hereinafter described more fully. The movement is small, 120 being not more than half the diameter of a cap.

Each of the cap affixing plungers 9 is cylindrical and fits closely within the closure ring 44 and about the valve cylinder 49 in 125 130

telescopic relation thereto. Said plungers 9 are all actuated and controlled by a vertically movable horizontal frame or capper table 80 to which they are secured in yielding relation. Each plunger fits slidably in a vertical perforation in said capper table, and is prevented from complete withdrawal downward therefrom by means of a shoulder on its upper end, a threaded flange or ring 81 being used in this instance. Said plunger is urged downward by yielding means, as for instance, a coiled spring 82 acting between the under side of said frame, and a shoulder 84 on said plunger beneath said table. The spring 82 is strong enough to drive the cap into place with sufficient force to spring or deform the latter somewhat so as to set very tightly in the bottle. The capper table 80 is below the tops of the valve cylinders 49 and is formed to clear the bottle closure control rods 51, said table being apertured therefor.

Mechanism for controlling the filling means 6 is provided comprising a frame or filler table 86 which is movable vertically subject to automatic control. The movable member 42 of each filling tube is secured rigidly to said table, and may be screwed into a threaded perforation therein, as shown in Fig. 4.

Means for lowering and raising the filler tube frame 86 comprise automatically operated mechanism including a pair of like cam members 88 fixed in spaced relation on the horizontal power shaft 89, said members each being preferably in the form of a disk with a cam slot 91 in one of its radially disposed faces. Cooperating with each of said disks is a vertically disposed rod 92 with a cam engaging shoulder or pivot 93 on its lower end and having its upper end connected to said table 86, by which means a vertical reciprocating movement is produced.

Oscillating mechanism is provided for the swinging table 69 which carries the cap guides 8, said mechanism including a cam disk 95 fixed to the driving shaft 89 and a jointed rod 97 coacting therewith and extending upward to one arm of a bell crank lever 98, the arms of which are fixed on opposite ends of a journaled shaft 98'. From the other arm of lever 98 a link 100 extends to said rod 75 which is pivoted to the lever arms 74.

For operating the cap feeder mechanism there is provided an eccentric member 103 fixed to the shaft 89, said member being connected by means of a jointed pitman rod 105 to one arm of a bell crank lever 107 which lever also comprises a pivot shaft 110 and four other arms which are in turn connected by rods 109 to the cap feed plates 15.

Means for lifting the bottle platform are provided comprising a cam disk 115 fixed

on said driving shaft 89 and the upwardly projecting rod 35 having on its lower end a bearing roller 116 riding on the peripheral cam face of said disk, the platform 4 being supported on the upper end of said rod. Said cam face 118 is formed with inclined parts 119 connecting three main stages 124, 125 and 126 substantially concentric with shaft 89, whereby in operation the platform is first raised from its normal lowermost position to an intermediate position at which it bears against and supports the case bottom while the bottles are filled, and then after the filling tubes have been raised and the cap guides swung into position over the bottles the platform, lifting the case therewith, is raised to its uppermost position, and after the caps have been affixed the platform is lowered directly to its lowermost position and the box deposited on the rollers 38, whereupon the case is removed and a fresh case with empty bottles takes its place.

The mechanism for controlling the cap affixing plungers 9 comprises a pair of like cam disks 130 fixed to the shaft 89, and a pair of vertically disposed rods 131 disposed on opposite sides of the filling mechanism, the lower ends of which rods are provided with studs coacting with the cam slots 133 on said disks, and the upper ends being fixed to the capper table 80 which lifts and lowers the cap plungers 9. Said cams 130 are formed so as to lower the cappers 9 part way, with the fillers 42, sufficiently to maintain a liquid tight joint with respect to the closures 44, and when tubes 42 are raised the cams 130 drive the plungers 9 down alone.

Guide means for the vertical operating rods 92, 97, 105, 116 and 131 are provided, cross bars 135 fixed to the frame 1 being shown in this instance, said bars being provided with bearings to limit the movement to vertical reciprocation.

Power for driving the shaft 89 may be transmitted thereto by any suitable means, such as a gear 136 and worm 137 mounted on a driving shaft 138.

When automatic case feeding is provided, a gear 140 is fixed on the shaft 89.

The several said actuating means fixed on the driving shaft 89 are so related with respect to their relative angular operating positions on said shaft that when the case feeder 17 stops the several bottling operations are carried out in a definite predetermined order substantially as follows:

1. The cam 115 raises the platform 4 to its intermediate or filling position to support the bottles without raising them.

2. The cams 88 then operate to lower the filler tubes 42 and closure members 44 for filling the bottles and thereupon restore the same.

3. The guide oscillating cam 95 then 130

swings the frame 69 forward to place the guides and centering bells over the bottles and in registry with plungers 9.

4. Cam 115 then raises the platform 4 to its uppermost or capping position.

5. The capping cams 130 then lower the plungers and immediately restore the same.

6. The cam 95 then restores the guides to their normal position adjacent to the cap 10 magazines.

7. The cam 115 then lowers platform 4 to its normal lowermost position to exchange boxes 36.

8. The eccentric member 103 then moves 15 the cap feeder plates 15 forward to deposit a cap in each of the guide cylinders 65 ready for the next operation. This last mentioned operation may take place during the time that the cases are being exchanged 20 and the bottles are being filled, the eccentric actuating means being timed accordingly. Some of the other operations may be more or less simultaneous or overlapping, depending on the relative setting of the 25 cams.

The operation of the filling and capping mechanism is as follows: A case filled with empty bottles being slid into place, the machine thereupon runs through its several 30 operations automatically, as above enumerated. As soon as the platform is lowered after the capping operation, the case containing the filled bottles is removed and replaced by another case containing empty 35 bottles.

The said means 17 provided for feeding the bottle cases 36 into and discharging them from the machine automatically, comprises an endless chain or belt member, the upper 40 or active part of which travels along a track or guideway 142 on the bracket 39 on each side, and serves as a positive feed or driver by which the cases are carried into and through the machine.

45 The said endless means or case carrier includes a pair of sprocket chains 143 spaced apart to coact with and support the sides of said cases. Said chains are provided with shoulders 144 adapted to engage the case for urging it forward by positive and definite action. These chains are carried on sprockets 146 arranged in pairs at each end of the carrier. The sprockets on one end are mounted on a shaft 148 provided with a 50 third sprocket 149 which coacts with a chain 150. This chain in turn coacts with a sprocket 151 on a shaft 152 which is provided with a pinion 154 which in turn coacts with the said large gear 140 on the main 55 driving shaft 89.

Said pinion and gear are formed for periodic intermittent turning of the pinion, said large gear being provided with teeth only on part of its periphery, preferably 60 about 90 degrees, the remaining 270 degrees

being without teeth, so that as the large gear turns uniformly it will operatively engage the pinion only while turning through one-quarter of its complete revolution; hence the case feeder remains at rest about 75 per 70 cent of the time to accommodate the filling and capping operations. As no novelty is claimed for the specific form of gear and pinion, and as intermittent gears are well known in the art, it is believed to be unnecessary to describe the same more in detail. 75

The said carrier 17 is disposed crosswise of the machine and extends substantially from one side to the other. An intake platform 158 is provided on one side of the machine 80 in alignment with said carrier, said platform preferably being inclined downward toward the carrier and provided with antifriction bearings or rollers 159 permitting the cases to feed forward to the carrier by gravity. 85 Said platform may be large enough to receive a long row of cases filled with empty bottles, which cases will be fed into the machine automatically without any attention from the person in charge of the machine. 90

A discharge platform 161 is provided in the opposite side of the machine also adapted for moving the cases automatically, said platform preferably being inclined downward away from the machine and provided 95 with anti-friction bearings or rollers over which the cases will pass freely and so be conducted by gravity to any point desired, as for instance, to a cold storage room or refrigerator. 100

Means are provided for starting and stopping the machine automatically when work is commenced and finished respectively. When the first case 36 rides down the supply platform 158 it is arrested by a laterally 105 yielding stop 163 adjacent to the carrier. As the case comes to rest against said stop it coacts with a yielding contact 164 arranged to close the circuit extending from any suitable source, as a generator 165, to the electric 110 motor 166 which drives the machine. Thereupon the machine starts, and the carrier is caused to advance, whereby the shoulder 167 on the carrier chain 143 pushes back the stop shoulder 163 so as to release said 115 case and permit it to advance onto the carrier, said stop having a depending curved part 163' formed to so coact with the release shoulder 167. Guide means 168 are provided on the frame 1 opposite the spring 120 163 to keep the carrier chain 143 in place when the lateral shoulder 167 acts on the spring 163. Furthermore, positive means are provided for coaction of the carrier with the forward part of the case, the said shoulder 144 being formed to coact with a definite part of the case as for instance the transverse bar 169 on the front thereof between the downward flanges of the case. As the carrier moves forward the shoulder 144, co- 125

130

acting with said bar 169, draws the case into the machine.

When the carrier stops by reason of the intermittent gear above described, the case is thereby brought to rest in registry over the lift means 4 and in due coöperative position under the filler and capper means. As the case thus moves forward to its operative position in the machine it coacts with a second yielding contact 171 whereby the motor circuit is caused to be closed at another point so that the machine will continue to operate even though the first contact 164 should be left open.

15 When the bottles in said case have been filled and capped, the intermittent gears again advance the carrier and deliver the case onto the discharge platform 161. As said case passes from its operative medial 20 position in the machine it actuates a third contact 172 also arranged to close the motor circuit, so that the machine will continue to run until said case has been entirely discharged from the machine, regardless of 25 whether the first two contacts are closed or not. Said contacts are connected in parallel so that closure of any one or more will serve to keep the machine running.

So long as the cases are fed to the machine 30 continuously, the motor circuit will be kept closed by said contact means, but when the last case passes from the machine the circuit will be left open and the machine will stop automatically.

35 As the machine normally stops as soon as the last case passes from the machine, it is necessary upon starting for the main shaft to turn through the filling and capping part of its cycle before the mutilated gear 140 will 40 become effective for advancing the case carrier and the first oncoming case. The filler in the meantime will operate as usual except that the valve 49 will remain closed, there being no bottle to arrest the downward 45 movement of the closure member 44. The swinging table 69 during this idle cycle would receive and uselessly discharge a set of caps, but for the presence of means dependent on the presence of a case in the machine for throwing the cap feeders 15 into and out of operating gear, as for instance an electromagnetic clutch having a circuit including contacts similar in position and operation to those shown in Fig. 12, as will be 55 understood.

The case feeding means above described may be used not only in a machine including both filling and capping means, but equally well in a machine adapted for filling or capping only respectively.

60 The valve 49 may be set to close sooner or later, by adjusting the threaded bolts 51, so as to cause the liquid to stand at the exact level desired in the bottle when filled. The 65 form of filler tube or nozzle shown in Fig.

16 is well adapted for use where precision is required, as the discharge ports are at the lowest extremity of the nozzle, and the liquid will rise to a plane substantially level with the lower edge of the valve cylinder 70 as the nozzle is raised and the ports closed by said valve. The modified parts shown in said Fig. 16 correspond substantially with the somewhat similar parts shown in Fig. 4, and are indicated for convenience by like 75 numerals respectively with prime marks affixed.

Although but one feature of the invention, namely, the discharge nozzle, is herein shown and described in more than a single 80 specific embodiment, it will be understood that numerous details of the construction of the bottling machine as a whole may be altered or omitted without departing from the spirit of this invention as defined by the 85 following claims.

We claim:

1. In a capping device of the character described, double centering means for the bottle to be capped comprising complementary inclined parts downwardly divergent with respect to each other and adapted to receive the rim of the bottle mouth, said means being relatively movable in a direction parallel with the longitudinal axis of the bottle, 90 and the inner of said parts having its inner face alined with the inner face of the top part or flange of the bottle mouth for guiding caps into place therein.

2. In a bottle capping machine, a bottle-positioning bell having a frusto-conical extremity adapted to receive the mouth of the bottle, and being spring-pressed into yielding engagement therewith, a hollow cylindrical cap guide axially movable inside the 100 bell into and out of engagement with the bottle's mouth, and a plunger adapted and arranged to force a bottle cap through the guide and into the mouth of the bottle.

3. A bottling machine, comprising a cap 110 magazine and a cap setter disposed side by side, cap carrying means including a member movable to and from a position under and in alinement with said cap setter, said member being formed with downwardly divergent parts adapted to engage and center the bottle in alinement with said cap setter when the bottle is raised, and means for raising the bottle and supporting it while being 115 capped.

4. In a bottling machine, a cap guide cylinder, in combination with a bottle centering bell concentric therewith and fitting telescopically thereon, each having an outward flange at its upper end respectively and supporting means bearing normally against the under side of the flange of the bell member.

5. In a bottling machine, a plurality of cap magazines and feeders and corresponding cap guides, and bottle centering bells in 120 130

combination with a guide frame pivotally mounted for lateral swinging and movable to carry said guides and bells to and fro between the cap feeders and the bottles.

5 6. A bottling machine, comprising a cap conveyer including a receptacle adapted for receiving and carrying the caps successively, said receptacle being movable to one position for receiving a cap and to another position over the bottle for discharging the cap, means for raising the bottle to coact with said receptacle, means for transferring the cap from said receptacle and applying it to the bottle, and yielding means for actuating said transferring means, said receptacle being yieldably mounted for upward movement when urged by coaction with the upwardly moving bottle.

7. A bottle capping device comprising a 20 tubular cap guide formed with its inner surface substantially co-cylindrical with the mouth of the bottle, in combination with a cap setting plunger fitting closely within said guide, said plunger being formed to bear solely on the peripheral margin of the cap, and said guide being formed interiorly of somewhat less diameter than the cap adjacent to its discharge end, whereby the cap is contracted and bulged somewhat as it is 25 forced to its seat, and is so caused to fit tightly in the bottle.

8. In a bottling machine, a horizontal frame member, a cap magazine mounted above and adjacent thereto, feed means carried by said frame member for feeding caps laterally from said magazine, reciprocating cap carrier means disposed beneath said frame member and feed means, and movable from said feed means to a position over 40 the bottle to be capped, said feed means and frame member having apertures to register over the retracted position of said carrier at one side of said magazine.

9. In a bottle capping machine, a cap 45 conveyer movable to one position to receive a cap and to another position over the bottle to discharge the cap, means for raising the bottle to press against said conveyer, means for transferring the cap from said conveyer to the bottle and applying it to the latter, and yielding means for actuating said transferring means, said conveyer being yieldably mounted for upward movement when urged by the bottle.

55 10. In a bottle capping machine, a cap conveyer movable to one position to receive a cap and to another position over the bottle to discharge the cap, means for raising the bottle to press against said conveyer, 60 means for transferring the cap from said conveyer to the bottle and applying it to the latter, and yielding means for actuating said transferring means, said conveyer being yieldably mounted for upward movement when urged by the bottle, and com-

prising a cylindrical cap guide proper and a bottle centering bell mounted telescopically thereon, said bell having a spreading flange to receive the top of the bottle, and yielding means for urging said bell downward. 70

11. A bottling machine, comprising a frame, a carrier thereon for conveying cases of bottles through the machine, automatic means for feeding the cases to the carrier, 75 means for applying caps to the bottles, automatic means for discharging the cases from the machine, automatic means for starting the machine operable by the first case to enter the machine, and means for keeping 80 the machine running as long as the cases are being supplied to and fed through the machine, said last mentioned means being adapted for stopping the machine automatically when the last case passes from 85 the machine.

12. A bottle handling machine, comprising a frame, a shaft driven at a substantially constant speed thereon, a case carrier, means operable intermittently connecting said carrier and said shaft, and means positioned on said carrier in definite time relation to said shaft for positively engaging the cases to place the latter for capping in a certain definite operating position in the machine. 90

13. A bottling machine, comprising a frame, a case carrier supported thereby, means for driving said case carrier intermittently, automatic means for capping the bottles when the carrier is at rest, means whereon the cases are fed to the carrier, stop means formed and arranged to check the advance of the cases onto the carrier, and means operable by the carrier for 100 releasing said stop means so that the case is permitted to advance upon said carrier. 105

14. A bottle capping machine, comprising a frame, a case carrier mounted on said frame, capping means disposed above said carrier, driving means operable at a substantially constant speed for actuating said capping means and carrier, said carrier having intermittently operable connection with said driving means, and means disposed at intervals along the length of said carrier adapted for engaging the bottle case at a plurality of points whereby the forward end of the case may be positively engaged for drawing the case onto the carrier and whereby the rear part of the case may be urged positively from the machine. 110

115 15. A bottle capping machine, comprising capping mechanism and means for supporting the same in operative position, a carrier for bottle cases disposed beneath said mechanism, means for feeding cases automatically to said carrier, means for removing the cases automatically from said carrier, correlated means for driving said carrier and 120 130

mechanism, and automatic starting and stopping means actuated by the bottle cases.

16. A bottling machine, comprising a frame, capping mechanism thereon, inclined automatic supply and delivery platforms disposed on opposite sides of said frame, an endless unidirectional carrier disposed between said platforms, and driving means operatively connected to said carrier and mechanism for moving the same correlatively.

17. In a bottling machine, means for feeding cases of bottles automatically to and transmitting them through and from the machine, capping means positively interrelated operatively with the case feeding means, and power connecting means operable automatically by the cases for turning on and off the power for driving the machine.

18. A frame, a unidirectional conveyer thereon, supply and discharge platforms arranged in effective relation to said conveyer whereon bottle cases or the like may be transmitted automatically to and from said conveyer respectively, retractable check means arranged to stop the cases on the supply platform, means at a definite point on said conveyer adapted to retract said check means so as to permit the advance of the

case upon a certain part of the conveyer, means at a definite point on said conveyer adapted to engage a certain part of the oncoming case so as to insure a definite position of the case on the conveyer, means for halting the conveyer at a certain position, and automatic capping means operable when said conveyer is at rest.

19. In a machine of the character described, a horizontally traveling belt conveyer adapted to receive and support a case of bottles, a guide communicating with said conveyer and adapted to transmit a case of bottles thereto, a second guide adapted to receive a case of bottles from the conveyer, means for intermittently driving the conveyer, automatic means for capping the bottles when the case is on the conveyer, means operable in connection with the traveling movement of the conveyer for effecting the movement of the case from the first guide to the conveyer, and means operable in connection with the traveling movement of the conveyer for positively engaging the case and moving it to the second guide.

Signed at Chicago this 3rd day of March 1916.
